UNITED STATES PATENT OFFICE.

WALTER W. MACFARREN, OF PITTSBURG, PENNSYLVANIA, ASSIGNOR TO WILLIAM H. DONNER, OF PITTSBURG, PENNSYLVANIA.

AUTOMOBILE.

No. 876,070.

Specification of Letters Patent.

Patented Jan. 7, 1908.

Application filed July 23, 1906. Serial No. 327,328.

To all whom it may concern:

Be it known that I, WALTER W. MACFARREN, a resident of Pittsburg, in the county of Allegheny and State of Pennsylvania, have invented a new and useful Improvement in Automobiles; and I do hereby declare the following to be a full, clear, and exact description thereof.

My invention relates to automobiles, and more particularly to heavy trucks for merchandise, or large passenger vehicles.

The objects of my invention are to provide means for applying the driving force of a single motor to all four wheels of the vehicle; to provide for an equal braking effect on all four wheels; to incase and protect the driving mechanism; to provide a simple, substantial and very flexible running gear, and to provide improved means for steering all four wheels by means of which I can steer both the front and rear wheels independently by hand, or simultaneously, by hand or power, in the same or opposite directions, and by which I may also steer the front wheels independently by power.

To these ends my invention comprises the novel features hereinafter set forth and claimed.

In the accompanying drawings Figure 1 is a side view of an automobile embodying my invention; Fig. 2 is a plan view showing the steering mechanism; Fig. 3 is an enlarged detail of the steering mechanism; Fig. 4 is a front elevation; Fig. 5 is a front elevation partly in section; Fig. 6 is a plan view of the driving shafts and gears in section; Fig. 7 is a detail of the lever mechanism for steering by power; Figs. 8 and 9 are sectional views showing the action of the clutch gear in steering; Fig. 10 is an enlarged detail of a portion of the hub; and Figs. 11 and 12 are diagrammatic views illustrating the position of the wheels in steering.

In the accompanying drawings I have illustrated my invention in connection with a large truck or dray for the hauling of heavy loads, and to which my invention is particularly applicable, although it may be applied to any of the many forms of self-propelled vehicles. The numeral 2 designates the body or frame of such a vehicle which is supported by the trucks 3.

The engine 4 may be of any suitable type, and is connected by a chain drive to the

sprocket-wheel 5 on the shaft 6, which is inclosed within the sleeve or casing 7. On the shaft 6 is the pinion 8, which meshes with the gear 9 on the sleeve 10, which is loosely mounted on the shaft 11. A casing 10^a is connected to the sleeve 10 and mounted on the stubs 10^b are the bevel pinions 10^c. These pinions 10^c mesh with the bevel gears 13 and 13^a, keyed to the shaft sections 11 and 12, respectively. It will be apparent that both shaft sections 11 and 12 will be driven in the same direction and a differential gear is provided for any variation in speed of rotation of said sections, due to passing over uneven places in the roadway. A suitable brake band 13^b surrounds the casing 10^a.

The shafts 11 and 12, together with the gear and differential gear mechanism, are all inclosed within the shell 14, which is made up of parts bolted together and extends from one axle to the other, so as to inclose all the parts and guard them from dust and dirt. The shell 14 is secured rigidly to the front-body by the bolts 14^a, and at its rear end enters the sleeve 14^b so as to turn freely therein. A collar 14^c is screwed on to the shell 14 to prevent its withdrawal from the sleeve 14^b. The shell may be termed a reach-bar, and the rear axle casing with its sleeve 14^b is adapted to move independently of the reach-bar. Either of the rear wheels may descend into a rut and the axle assumes its position without affecting the reach-bar. The reach bar 14 is preferably arranged to one side of the longitudinal center line of the vehicle so as to provide for the proper arrangement of the gears and differential upon the shafts 17 and 18. The reach bar is torsionally flexible owing to the fact that it enters the sleeve 14^b so as to freely turn therein, while at its opposite end it is rigidly connected to the front body by the bolts 14^a.

At the end of the shafts 11 and 12 are the bevel pinions 15, which mesh with the bevel gears 16 upon the axle shafts 17 and 18, being the front and rear axles respectively. As the same construction is followed on both axles a description of one will suffice. The axle shafts are arranged in the center bearings of the axle casing 18^a, said casing being preferably formed in three sections bolted together by the bolts 18^b. The middle section of the axle casing forms the chamber 18^c. Access is had to this chamber 18^c by means of the door 18^d for the purpose here- 110

inafter set forth. The axles are made in two parts, 19 and 20, and a differential gear 21 is employed at the point of connection of the two parts of the axle, the same as employed above, so as to provide for the variations in speed of rotation of said axle sections. The bevel gears 15 and 16 and the differential gear 21 are all contained within the chamber 18^c and by reason of the door 18^d these parts are all readily accessible for purposes of inspection and repair. The differential gear 21 is also provided with a brake 21^a.

On the outer ends of the axle sections 19 and 20 are the clutches 22, which are adapted to slide upon the axles; and springs 23 are interposed between the collars 22^a on said axles and said clutches so as to normally force said clutches outward. These 20 clutches are feathered to the axles so as to rotate therewith. These clutches 22 engage corresponding clutches 24 on the wheels, and in this manner the wheels 25 are driven. The construction of these clutch faces is 25 clearly shown in Figs. 8 and 9, there being two sets of teeth in each clutch face, the inner set 26 engaging for the full depth of the teeth while the outer set 27 only engages for part of their depth so as to provide for 30 the throwing of the wheel at an angle in steering, as fully hereinafter set forth. Annular flanges 27^a divide the rows of teeth, and said flanges are adapted to bear against each other for the purpose of keeping the 35 teeth of the clutches in proper engagement. By this construction it is apparent that the axle shaft and stub shaft are in operative engagement with each other whether said shafts are in line with each other or intersect each other, as indicated in Fig. 9.

The clutches 24 form part of the stub axles 24^a, which pass through the axle-boxes 28. A threaded bolt 24^b secures the hub 25^a to the stub-axle 24^a. On the other end 45 of stub-axle 24^a are the teeth 24^c, which mesh with corresponding teeth 25^b on the hub 25^a. The hub 25^a has also the teeth 25^c which engage the teeth 25^d in the collar 25^e of the wheel. Roller bearings 25^f are provided. By the above construction the 50 power is transmitted from the stub-axles to the wheels.

The wheels are pivotally mounted so as to turn independently on the main axles. 55 The axle-boxes 28 are provided with the brackets 28^a through which the bolts 29 pass to swivel the wheels to the axle casing. The axle casing is provided with the lugs 18^e through which the bolts 29 pass. These 60 bolts 20 are threaded at their lower ends into openings in the brackets 28^a and in this way the said bolts rigidly connect the separate lugs of the brackets 28^a in such a manner that all four of said bracket lugs support the weight of the wheel. By having 65

said brackets above and below the axle, the wheel is more evenly balanced and supported. The construction of the wheels may vary and as the particular make-up of the wheel forms no part of my invention, I have 70 not described the same in detail.

Located in convenient position with reference to the seat of the vehicle is the hand-wheel 30, which is keyed to the shaft 31 and controls the rear wheels. This shaft 31 has 75 at its lower end the bevel gear 32, which meshes with the bevel gear 33 on the shaft 34. The shaft 31 passes down through the hollow shaft 35, and to this hollow shaft 35 is keyed the hand-wheel 36, which controls the 80 front wheels. At the lower end of the hollow shaft 35 is the bevel gear 37 which meshes with the bevel gear 38 on the hollow shaft 38^a which surrounds the shaft 34.

Keyed to the hollow shaft 35 is the clutch 85 39, and pinned to the wheel 30 is the clutch 40. A clutch 41 is pinned to the bevel gear 42 loosely mounted on the hollow shaft 35. A pinion 43 is loosely mounted upon the stub or pin 44, and said pinion meshes with the 90 bevel gear 45 keyed to the hollow shaft 35. Above the wheel 30 is the cam latch 46 with the pin 47 adapted to enter the recess 48 in the shaft 31. The pin 47 has the slot 47^a through which the pin 30^a passes, connected 95 to the hub 30^b of the wheel 30.

The wheel 30 controls the rear wheels of the vehicle and the wheel 36 controls the front wheels, so that said wheels may be steered independently of each other. 100 Through the clutch mechanism described, however, all four wheels may be operated by the hand-wheel 30 and this clutch mechanism is controlled by the latch 46. By throwing the latch to the right, the clutch 40 will be 105 thrown up into engagement with the clutch 39, so as to operate both the front and rear wheels in opposite directions, to produce radial steering. By throwing the latch 46 in the opposite direction, the clutch 40 may be 110 thrown into engagement with the clutch 41, and thus reverse the direction of steering of the rear wheels to produce oblique steering.

Secured to the shafts 34 and 38^a are the worms 50, which are adapted to engage the 115 quadrants 51 pivoted at 52. These quadrants have the arms 53 which are connected to the links 54 secured to the arms 55 upon the brackets 28, by means of which the wheels are swiveled on the bolts or pins 29. 120 It is apparent that by rotating the shaft 34 and the worm 50 through the connections described, the rear wheels are turned in either direction as desired.

In case it is desired to operate the steering 125 mechanism by power transmitted from the engine, I provide the friction wheel 56 upon the hollow shaft 35, said friction wheel to be driven in opposite directions as desired by means of the friction pinion 57, which is 130

adapted to engage the opposite faces of said friction pulley. This friction pinion 57 is mounted on the stub-shaft 58 which carries the sprocket-wheel 59 connected to the engine shaft, or to the transmission. A lever 60 is employed for throwing the friction pinion 57 into engagement with opposite faces of the friction wheel, 56, in order to change the direction of rotation of the shaft 35. It is apparent that by throwing the clutch mechanism so as to bring the shafts 31 and 35 into engagement both the front and rear wheels can be operated simultaneously by the power mechanism described. The springs 15 for supporting the vehicle body which I have not described, form the subject matter of an application filed by me on the 28th day of May, 1906, Serial No. 319,126.

When my invention is in use the power will be transmitted from the engine through the sprocket wheel 5 and shaft 6 to the shafts 11 and 12, and thence to the axles. The rotation of the axles with the clutches 22 in engagement with the clutches 24 will act to drive the wheels and so propel the vehicle. When it is desired to turn a curve the operator, by turning the hand-wheel 36 in the proper direction, throws the front wheels into the proper position for turning, and at the same time throws the rear wheels into the opposite direction, as clearly indicated in the diagrammatic view Fig. 11. In this manner both the front and rear wheels are operated positively in turning so that the vehicle may be turned about a shorter radius and in less space than if only one set of wheels are steered, and the rear wheels assume the proper line to conform with the circle made by the vehicle in turning. In case it is desired to drive the vehicle from the center of the street to the curb, the operator is able to throw all four wheels into the same direction by operating the latch so as to throw the clutch on the wheel 30 into engagement with the clutch 41 on the hollow shaft 35, so that by the turning of the wheel 30 both sets of wheels are turned in the same direction as indicated in Fig. 12. In this way the vehicle may be shifted sidewise, remaining always parallel to its former line of direction. In the shifting of the wheels in steering, it is apparent that the teeth on one side of the clutches 22 and 24 will be thrown out of engagement, while those on the other half will be engaged so that the power is transmitted from the axles to the wheels. In such case the clutches 22 are forced back on the axles and the springs 23 compressed. By my invention, therefore, I provide for the driving of the four wheels of the vehicle in a positive manner, any difference in the speed of rotation being taken up by the differential gears provided, while at the same time the parts are also inclosed so as to protect the running gear from dust and dirt. Fur-

thermore, the steering mechanism provided makes it possible to steer the front wheels independently or simultaneously with the rear wheels, so that said wheels may be thrown in opposite directions or in the same direction, as may be desired, by either hand or power.

What I claim is:

1. The combination with a vehicle, of steering mechanism comprising a substantially vertical sectional steering shaft, connection between each section of said shaft and a pair of wheels to steer the same, and a clutch mechanism adapted to connect the said shaft sections so that they will rotate either in the same or opposite directions.

2. The combination with a vehicle, of a substantially vertical sectional steering shaft, connections between each of said shaft sections and a pair of wheels to steer the same, a hand wheel connected to one of said shaft sections, a second hand wheel connected to the other of said shaft sections, each hand wheel operating a different pair of wheels, and a clutch mechanism adapted to connect the said first shaft section with the said second shaft section whereby all four wheels may be steered by the use of one hand wheel simultaneously in either direction.

3. The combination with a vehicle, of a pair of hand wheels, connections between said hand wheels and the vehicle wheels to steer the same independently of each other, and means for connecting said hand wheels to rotate in opposite directions.

4. The combination with a vehicle, of axles, pivotally mounted wheels, two operative shafts, one for the front wheels and one for the rear, connections between said shafts and said wheels to steer the same, an operative shaft normally in driving engagement with one of said shafts, a second operative shaft normally in driving engagement with the other shaft, clutches on one of said operative shafts, and a movable clutch on the other of said operative shafts between the first clutches, means for moving said movable clutch into engagement with either of said clutches on said operative shaft, and reverse gear mechanism on said last named shaft.

5. The combination with a vehicle, of axles, pivotally mounted wheels, two operative shafts, one for the front wheels and one for the rear, connections between said shafts and said wheels to steer the same, an operative shaft normally in driving engagement with one of said shafts, a second operative shaft normally in driving engagement with the other shaft, clutches on one of said operative shafts, a movable clutch on the other of said operative shafts between said first named clutches, a cam latch for moving said movable clutch into engagement with either of said clutches on said other operative shaft,

and reverse mechanism on said last named shaft.

6. In a vehicle, the combination of four steerable wheels, means for steering either the front or rear wheels independently by hand, or all four wheels simultaneously by hand, and means for steering the front wheels only or all four wheels by power.

7. In a vehicle, the combination of four steerable wheels, an engine or motor, means for steering the front wheels only, or the front and rear wheels simultaneously by power from said engine or motor.

8. In a vehicle, the combination of four steerable wheels, a motor or engine, means for steering all four wheels simultaneously in either the same or opposite directions by power from said motor or engine.

9. The combination with a vehicle, of axles, pivotally mounted front and rear wheels, a shaft, connections between said shaft and one of said set of wheels to steer the same, an operative shaft normally in driving engagement with said first named shaft, and connections between said operative shaft and a motor or engine.

10. In a vehicle, the combination of axles, pivotally mounted front and rear wheels, two rotative shafts, one for the front and one for the rear wheels, connections between said shafts and said wheels to steer the same, an operative shaft normally in driving engagement with one of said shafts, a second operative shaft normally in engagement with the other shaft, a motor or engine, means for bringing said operative shafts into engagement with each other, and connections between said operative shafts and said motor or engine.

11. In vehicles, the combination of axles, of pivotally mounted front and rear wheels, two rotative shafts, one for the front and one for the rear wheels, connections between said shafts and said wheels to steer the same, an operative shaft normally in driving engagement with one of said shafts, a second operative shaft normally in engagement with the other shaft, means for bringing said operative shafts into engagement with each other, a frictional pulley on one of said operative shafts, a friction pinion adapted to engage opposite faces of said pulley to reverse the direction of rotation, an engine or motor, and means for driving said pinion from said engine or motor.

12. In vehicles, the combination of a horizontal worm shaft, a worm on said shaft, a worm sector engaged by said worm and connected to a pair of wheels to steer the same, a hand wheel connected to said worm shaft, a second horizontal worm shaft, a worm on said shaft, a worm sector engaged by said worm and connected to a second pair of wheels to steer the same, and a second hand

wheel connected to said second worm shaft to steer said second pair of wheels.

13. In vehicles, four steerable wheels, a worm shaft parallel to the longitudinal center line of the vehicle, a worm mounted on said shaft adapted to steer a pair of wheels, a second worm mounted on said shaft and adapted to steer the second pair of wheels, a hand wheel, and connections between said hand wheel and said worm shaft to control the movement of the same.

14. In vehicles, the combination of a suitable engine or motor, an axle driven thereby, pivotally mounted wheels, a spring actuated toothed clutch on said axle, and a clutch on said wheel engaged thereby.

15. In vehicles, the combination of a suitable engine, or motor, an axle driven thereby, pivotally mounted wheels, a yielding circular toothed clutch on said axle, and a clutch on said wheel engaged thereby.

16. In vehicles, the combination of a suitable engine or motor, an axle driven thereby, pivotally mounted wheels, a yielding circular toothed clutch having an inner and outer row of teeth, and a clutch with a like inner and outer row of teeth on said wheel engaged thereby.

17. In vehicles, the combination of a suitable engine or motor, an axle driven thereby, pivotally mounted wheels, a yielding circular toothed clutch having an inner and outer row of teeth, and a clutch with a like row of teeth on said wheel engaged thereby, the inner sets of teeth overlapping more than the outer.

18. In vehicles, the combination of a suitable engine or motor, an axle driven thereby, pivotally mounted wheels, a yielding circular toothed clutch having an inner and outer row of teeth, and a clutch with a like inner and outer row of teeth on said wheel engaged thereby, with annular flanges between said rows adapted to engage each other.

19. In vehicles, the combination of an axle, a stub axle pivoted thereto, a driving shaft carried by said axle, a wheel on said stub axle, a second driving shaft connected to said wheel, and a spring actuated clutch connecting said driving shafts.

20. In vehicles, the combination of an axle, a stub axle pivoted thereto, a driving shaft carried by said axle, a wheel mounted on said stub axle, a toothed clutch member carried by said driving shaft, a second toothed clutch member meshing with the first clutch member, and connections between said second member and the wheel to drive the latter.

21. In vehicles, the combination of an axle, a driving shaft carried therein, a stub axle pivoted to said axle, a wheel mounted thereon, and a pair of clutch gears for transmitting power between the driving shaft and

the wheel, said clutch gears acting like a toothed clutch when the axle and stub axle are in line, and like a bevel gear when the same are at an angle to each other.

5 22. In vehicles, the combination of an axle, a stub axle pivoted thereto, a driving shaft carried by said axle, a wheel mounted on said stub axle, a yielding circular toothed clutch member on said driving shaft meshing with a corresponding clutch member in driving connection with the wheel.

23. In vehicles, the combination of two shafts normally in line but capable of being thrown in position at an angle to each other, 15 toothed clutches on said shafts in engagement with each other, a flange on each of said clutches limiting their engagement, and a spring for holding said clutches in mesh.

24. In vehicles, the combination of wheels, 20 axles, and a torsionally flexible reach bar

connecting said axles and rigidly fastened to said axles.

25. In vehicles, the combination of wheels, axle casings, and a torsionally flexible and laterally rigid reach bar connecting said axle 25 casings and rigidly fastened thereto.

26. In vehicles, the combination of wheels, axles, a tubular reach bar connecting said axles, said reach bar being arranged to one side of the longitudinal center line of the vehicle, a power shaft within said reach bar, and connections between said power shaft and said wheels.

In testimony whereof, I the said WALTER W. MACFARREN, have hereunto set my hand. 35

WALTER W. MACFARREN.
